(57) **CLAIM**

The ornamental design for a pet waterproof pad, as shown and described.

DESCRIPTION

FIG. 1 is a front perspective view of a pet waterproof pad, showing my new design;

FIG. 2 is a front elevation view thereof, the rear elevation view is identical;

FIG. 3 is a left side elevation view thereof, the right side elevation view is identical;

FIG. 4 is a top plan view thereof, the bottom plan view is identical;

FIG. 5 is a partial enlarged view of FIG. 1;

FIG. 6 is a partial enlarged view of FIG. 1;

FIG. 7 is a partial enlarged view of FIG. 1;

FIG. 8 is a partial enlarged view of FIG. 1;

FIG. 9 is a partial enlarged view of FIG. 2;

FIG. 10 is a partial enlarged view of FIG. 3; and,

FIG. 11 is a partial enlarged view of FIG. 4.

The broken lines in the drawings show portions of the pet waterproof pad which form no part of the claimed design. The dash-dot broken lines demarcate enlarged areas and form no part of the claimed design.

1 Claim, 10 Drawing Sheets(56)
